UNITED STATES PATENT OFFICE.

THOMAS T. GAFF, OF WASHINGTON, DISTRICT OF COLUMBIA.

CIRCUIT-CONTROLLER.

1,150,356.

Specification of Letters Patent. Patented Aug. 17, 1915.

Application filed March 3, 1914. Serial No. 822,218.

To all whom it may concern:

Be it known that I, THOMAS T. GAFF, a citizen of the United States, residing at Washington, in the District of Columbia, have invented certain new and useful Improvements in Circuit-Controllers, of which the following is a specification.

My invention relates to a circuit controller intended mainly for use in connection with 10 counters or other measuring instruments actuated by a series of electrical impulses produced by a make and break contact device connected or attached to some moving element, such as a rotating shaft. In devices 15 of this class, it may happen that the moving element stops, while the contacts are closed, thereby leaving the battery in a closed circuit which results in wasteful and possibly injurious discharge of the battery, 20 and produces other undesirable results.

It is the object of my invention to remove this difficulty by providing means for automatically breaking the battery circuit under such conditions and means for restoring 25 the circuit to proper indicating condition as soon as the moving element resumes its motion. These and other results I obtain by means of the mechanism illustrated in the accompanying drawings, in which,—

30 Figure 1 is a diagram of the system as a whole; and Fig. 2 is a plan view of the moving element, in this instance, a shaft.

Referring to the drawings, A is a shaft on which is mounted a flanged sleeve B, the 35 flange C having on its periphery one or more, preferably insulated, contact plates D. Arranged to engage this contact plate, at each revolution of the shaft, are contact springs E, F. From the spring E, the connections of what may be termed the "main circuit" are through wire 1, to indicator G, which may be of any suitable construction 40 and is provided with indicating or registering mechanism, actuated by the electrical impulses. From G the circuit is through wire 2 to battery H, wire 3, thermostatic circuit-closer 4, wire 5, switch lever K (pivoted on support L), contact M, wire 6, and spring F. The making and breaking of this otherwise 45 normally intact circuit operates the register or indicator G in any well known manner. If, however, the shaft A should stop in the position shown in Fig. 1, the continued flow of current through the thermostatic device heats the thermostat and causes 50 the closing of a secondary circuit from bat-

tery H through contacts N, O, wire 7, electromagnet P and wire 8, back to the battery. The magnet P is energized and attracts the lower end of the switch lever K and breaks 60 the contact between the upper end of the bar K and contact M, thus breaking the main circuit. As current has now ceased to flow, the thermostatic device cools down and breaks the secondary circuit at N, O, thus 65 deenergizing the magnet. To prevent the switch lever K from being retracted by the light spring T, I provide a latching device comprising a spring hook Q which engages a pin R secured to some stationary part of 70 the mechanism. In order to again restore the main circuit to its operative condition when the shaft again rotates, I provide the pin S on the face of the flange C and in such angular relation to the contact plate D that, 75 as soon as the contact is broken by the passing of the spring F off such plate, the pin S will engage the projection Q' on the end of the latch, raise the latch and permit the spring T to pull the switch lever K into contact with the terminal M, thus restoring the 80 main circuit to its normal operating condition. The magnet P is so proportioned as to exert enough pull to overcome the tension of the spring T.

The operation of the device will be readily understood from the foregoing description.

While I have described somewhat in detail a particular apparatus for accomplishing the results desired, it will be understood that the construction of the various parts may be widely modified without departing from the scope of my invention.

I claim:—

1. A circuit controlling device comprising a moving member, a circuit making and breaking device coöperating therewith and included in an electric circuit containing a battery, an indicating or registering device 90 and a switch, in combination with means for automatically operating said switch to break the circuit upon continued passage of the current therethrough, and means carried by the moving member to automatically restore 100 the circuit to normal condition, after being so broken.

2. A circuit controlling device comprising a moving member, a make and break device having one element thereof mounted on 110 said moving member, a switch, thermostatically-controlled means for opening said

switch, and automatic circuit-reëstablishing means carried by said moving member.

3. A circuit controlling device comprising a moving member, a make and break device having one element mounted on said member, a switch, thermostatically-controlled means for opening said switch, a latch having a member carried by said switch, and a pin on said moving member 10 for disengaging the latch.

4. A circuit controlling device comprising a rotating member, a make and break device having one element mounted on said rotating member, a switch, a thermostati-

cally-controlled means for opening said 15 switch, and switch-closing means carried by said rotating member, said means including a pin located in such angular relation with the make and break device as to cause the switch-closing means to operate as soon as 20 the make and break device breaks the circuit.

In testimony whereof I affix my signature in presence of two witnesses.

THOMAS T. GAFF,
